United States Patent Office.

WILLIAM C. DODGE, OF WASHINGTON, DISTRICT OF COLUMBIA.

Letters Patent No. 63,620, dated April 9, 1867.

IMPROVEMENT IN BOAT-DETACHING TACKLE.

The Schedule referred to in these Letters Patent and making part of the same.

TO ALL WHOM IT MAY CONCERN:

Be it known that I, WILLIAM CASTLE DODGE, of Washington city, in the county of Washington, and District of Columbia, have invented certain new and useful improvements in Boat-Detaching Apparatus; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel construction and arrangement of devices for detaching boats, as herein-after explained.

Figure 1 is a top plan view of a boat with my improvement applied thereto.

Figure 2 is a longitudinal vertical section of the same.

Figure 3 is a side elevation of a boat having the detaching applied in a different manner.

Figure 4 is a plan view of the locking-bar, shown detached.

Figures 5, 6, 7, 8, and 9 are views of portions detached, and of various modifications of the locking-bar.

In lowering and detaching boats from the sides of vessels, it is desirable to have both ends of the boat simultaneously and instantaneously detached, so that it may enter or strike upon the water as nearly as possible on a level, and so as to prevent one end from being loosened or detached while the other remains fast to the fall; as, when such an accident does occur, the end that remains fast is liable to be lifted clear of the water by the roll of the vessel, or by the depression of a wave at the loose end, and thus endanger the lives of the occupants and the loss of whatever the boat contains. To obviate the difficulties and dangers attendant upon the lowering and detaching of boats by the usual method, various plans and devices have been invented, the most obvious of which for detaching the boat are bolts to be withdrawn from eyes or rings attached to the falls. These devices are objectionable, for the reason that the locking-bolts, being attached to the rods or levers that operate them by means of loose joints or pivots, are liable to become detached separately, and as these detaching devices are of most importance in cases of accidents at sea, by the foundering or burning of the vessel, at which time the small boats are likely to be filled to their full capacity with persons, it is of the utmost importance that the detaching apparatus should operate with certainty and with success; and it is to insure these results that my invention is specially intended. For this purpose I take any ordinary small boat, and locate in its centre a rod B, as represented in figs. 1 and 2. This rod is secured under the seats or strong cross-pieces C, which should be firmly secured by rods or bolts to the bottom of the boat, to prevent their being loosened, the rod B having its bearings in suitable blocks or guides secured to the under side of the cross-pieces C, and arranged to slide to and fro therein. A rectangular hole or mortise is cut through the cross-pieces C, of proper size to receive the lower portion of the eye-block E, the form of which is shown in fig. 8. These eye-blocks are provided with shoulders which prevent their dropping entirely through the mortises, and have a hole through their lower portion of proper size to permit the end of bar B to enter with ease, their upper ends being provided with holes or rings to secure them to the falls by which the boat is suspended. The rod B has its rear end bent so as to turn or point forward in the same direction as its front end, as shown clearly in fig. 4, so that a forward movement of the rod will cause both ends to enter the holes in the eye-blocks, and a reverse movement of the bar will withdraw both from the eye-bolts simultaneously. A lever, L, is pivoted at one end under one of the seats, and is pivoted to the bar B, as shown in fig. 4, and also in dotted lines in fig. 1, by which the bar B may be operated. A spring-catch, l, or similar device, is arranged to hold the lever L in place and prevent the accidental disengaging of the bar B. By arranging the lever and its catch under the seat in this manner, I obviate the danger of their being accidentally or prematurely moved.

To use my device it is only necessary to insert the eye-blocks in the mortises, the bar B being drawn back for that purpose, and then shove the bar forward, when it enters the holes in the blocks at each end and securely fastens them in place. When the boat has been lowered, and it is desired to detach it, it is only necessary to draw the bar B back by pulling on the lever L, by which movement both ends of the bar will be simultaneously and instantly withdrawn from the eye-blocks, thereby detaching the boat at both ends with perfect certainty.

As the location of the bar B in the centre of the boat is objectionable in some cases, from the fact that it

may be in the way of boxes, barrels, and similar articles that it may be desirable to place in the boat, and for the reason, also, that such articles, in the hurry and confusion attendant on the lowering of the boats in case of shipwreck, fire, or battle, will be likely to be thrown or forced against the bar B, endangering the jamming or bending of the same, so that it will not work with ease and certainty, I have devised a plan for using the same suspended above the boat, as represented in fig. 3. To accomplish this I provide a light spar or bar, H, and attach it securely to the falls or lines, G, as shown in fig. 3. I then secure the locking-bar or rod B, constructed as already described, to the upper side of this spar H, in such a manner that when the eye-blocks E are inserted from below, through suitable mortises made in the spar, the ends of the locking-bar B will engage in the same and lock them securely in place, the same as when the bar B is located in the boat, except that the position of the eye-blocks and the bar is reversed, the parts being inverted. The bar B is held in guides, b, and is operated by an elbow-lever, F, as shown, or by any other suitable arrangement of devices. To prevent this lever from being accidentally moved, I provide a ring or loop, t, which is so hung that it will engage over the end of the lever and hold it securely in place; and to insure still greater certainty, I make a notch in the under side of the lever, to hold the loop t over the end of the lever F, as shown in fig. 3. By simply pulling down the end of the lever F the rod B will be thrown back, releasing both eye-blocks E simultaneously, and the latter being connected to the boat by short lines or ropes I, it is obvious that the boat will be thereby disengaged, and the spar H, with the locking-bar or rod B, will remain suspended by and attached to the falls G. For convenience, the line I should only be of such a length as to enable a person sitting on a seat in the boat to reach the lever F with ease.

As it will require considerable force to operate the locking-bar B when the whole weight of a boat, with its load, is held by it, I provide the end of the eye-blocks with friction-rollers, as represented in fig. 8, and also place friction-rollers under the bar B, as near as possible to the eye-blocks, as represented by r, fig. 3. When the bar B is placed in the boat the rollers r will be placed above the bar B, in the cross-pieces C, as shown in fig. 2, or in the guide-blocks attached thereto. To prevent the mortises or sockets in which the eye-bolts are inserted from being worn, and at the same time furnish a bearing for the rollers r, and a guide for the locking-bar B, I construct the box J, as shown in section in fig. 5. This box is cast in a single piece, with a vertical hole in the centre for receiving the eye-block E, and a projecting flange, h, for securing it in place by screws or bolts, and has a hole for the bar B to pass longitudinally through, as represented. This box is secured by bolts or screws to the under side of the cross-pieces C, as represented in fig. 5, when it is desired to locate the bar B in the boat, and the same box may be used when the bar B is used with the spar H, by simply inverting the box J and bolting it to the upper side of the spar.

Instead of making the locking-bar B as above described, and arranging it to move longitudinally, it may be constructed as represented in fig. 6, having its locking points bent at right angles to its body, and pointing in opposite directions to engage in the eye-blocks E, the bar in such case being pivoted at its centre, and arranged to rotate sidewise far enough to withdraw the locking points or arms from the eye-blocks. Or it may have its locking-arms both projecting from one side, as shown in fig. 7, the ends of the arms in such case being bent at right angles with their main portion, as shown in fig. 9, the bar B in that case being journalled, so as to rotate bodily, like a shaft, and thus withdraw the locking points from the eye-blocks. These latter plans, however, are but modifications of the one formerly described, and are not deemed as efficient as the former, for the reason that the springing of the rod or of the arms might possibly interfere with the simultaneous unlocking of the points at both ends. In applying my invention, I deem it of great importance that the locking points should both be rigidly attached to a solid bar, and thus avoid the intervention of any loose or working joint between the two locking points or bolts. In this way I secure absolute certainty in the simultaneous unlocking at each end, without which any boat-detaching device is imperfect and dangerous.

Having thus described my invention, what I claim, is—

1. A boat-detaching device, consisting of two locking points or bolts connected by a rigid sliding-bar, and having no loose or working joints between said locking points, arranged to operate in combination with the eye-blocks E, substantially as described.
2. I claim the sliding-bar B, having its rear end bent, as shown in fig. 4, for the purpose of enabling both ends to be disengaged from the eye-blocks simultaneously by a single movement, substantially as described.
3. I claim the combination of the sliding-bar B with the spar H, or its equivalent, when arranged for joint operation as and for the purpose herein set forth.

W. C. DODGE.
